UNITED STATES PATENT OFFICE.

HUGH P. McMILLAN, OF BALTIMORE, MARYLAND.

RAZOR.

1,058,318.

Specification of Letters Patent.

Patented Apr. 8, 1913.

Application filed February 17, 1912. Serial No. 678,277.

To all whom it may concern:

Be it known that I, HUGH P. McMILLAN, a citizen of the United States, residing at Baltimore, in the State of Maryland, have 5 invented certain new and useful Improvements in Razors, of which the following is a specification.

This invention relates to improvements in razors and has particular reference to a 10 razor having the general characteristics of the ordinary razor wherein the blade is pivotally connected to a slotted handle, but with improved means for attaching the blade.

An object of the invention is to provide 15 an improved construction of blade-carrying bar to which the blade proper may be readily attached or detached.

Another object is to provide improved 20 constructions for rigidly securing the blade to the bar that carries it.

A further object is to improve the construction of the guard and to provide an improved blade to coact with the bar and guard.

25 With these and other objects in view the accompanying drawing illustrates the invention, wherein,

Figure 1, shows the improved razor in side elevation as viewed from one side. Fig. 30 2, is a similar view of the razor but viewed from the other side. Fig. 3, is a side elevation of the detached blade-carrying bar. Fig. 4, a side view of the blade. Fig. 5, a side view of the detached comb. Fig. 6, 35 a cross-section on the line 6—6 of Fig. 1 showing the blade-carrying bar, the guard bar and the sliding clip plate. Fig. 7, is a cross-sectional view taken on the line 7—7 of Fig. 1, through the blade-carrying bar; 40 blade and guard, and Fig. 8, is a longitudinal side or edge view of the blade-carrying bar detached from the handle.

Referring to the drawing by numerals, 1, designates the handle of the razor having 45 the usual construction of razor handles of this character so that the blade-carrying bar, 2, may be pivotally mounted at one end thereof by means of a pintle, 3.

The blade-carrying bar is preferably a 50 stamped-up bar and has a central longitudinal channel or groove, 4, therein, which in the present instance, extends from end-to-end. At the outer end this bar is provided with a central back-turned hook, flange or 55 equivalent device, 5, which turns back at one side of but off-set from the channel or

groove, and the parallel sides of the bar at the opposite end are provided with flanges, 6, which beside strengthening the bar give breadth to said edges and afford a better 60 hold for the fingers during the operation of shaving. By referring to Fig. 8, it will be noted that the flanges, 6, do not extend the entire length of the bar but only for a portion of the length,—thus the outer end of 65 the bar is free of side flanges. The bar, 2, is also provided in its longitudinal channel or groove with positioning devices, 7, which in the present instance have the form of 70 projections, the purpose of which will presently be described. A perforation, 8, in the bar serves for the free passage of the pintle, 3, by means of which the bar is pivotally connected to the handle.

The blade, 9, has two longitudinal cutting 75 edges, 10, and on one side has a central longitudinal groove or channel, 11, while on the opposite side it is provided with a central longitudinal projection or rib, 12,—the rib being formed by punching the metal 80 outwardly at one side while producing the groove or channel at the opposite side of the blade.

The guard plate, 13, has a plurality of 85 teeth, 14, along its opposite edges and a plurality of intervening spaces, 15, between the teeth, as clearly seen in Fig. 5. This plate also has a central longitudinal depression, 16, along one side and a corresponding rib, 17, along the opposite side. A plurality of 90 positioning devices, 18, are provided on the guard plate and said devices are of a shape to coact with the positioning devices, 7, on the bar, 2. As the latter devices are circular projections the devices, 18, on the 95 guard plate are circular recesses so as to receive said projections. Obviously the shape of the projections and recesses are immaterial and it is also obvious that the projections and recesses may be reversed;—that is, 100 the bar, 2, may have the recesses and the guard plate the projections.

The guard plate has a reduced or narrow inner end, 19, preferably of substantially the same width as the bar, 2, and the groove or 105 channel, 16, extends throughout the length of this reduced inner end.

A clip plate, 20, is provided on the blade-carrying bar, 2, and said plate has its ends, 21, extending over and under the flanges, 6, 110 of the bar so as to slidably connect the clip with the flanged portion of said bar.

In assembling the parts to put the razor into condition for use, the bar, 2, is swung outwardly from the handle and the blade, 9, is laid against the bar with the longitudinal projection or rib, 12, of the blade seated in the longitudinal groove or channel, 4, of the bar, as shown in Fig. 7. In seating the blade against the said bar, 2, the same is pushed outwardly until one end of the blade projects beneath the back-turned hook, 5, at the outer end of the bar. The guard plate, 13, is then seated against the blade, 9, with the longitudinal rib, 17, of the guard entering the groove or channel, 11, in the blade, also as seen in Fig. 7. The outer end of the guard plate, when in position, projects beneath the hook, 5, on the bar, 2, which serves as a stop therefor, and the positioning devices, 18, at the inner end of the guard plate will coat and have engagement with the corresponding devices, 7, on the bar, so as to prevent rearward longitudinal movement of the guard plate on the bar. It will thus be seen that the guard plate and bar serve as clamps between which the blade is placed and when held together, the clip plate, 20, may be moved along the flanges, 6, of the bar until it passes onto the inner reduced end, 19, of the guard whereupon it will hold the positioning devices, 7, and, 18, in engagement and thus securely clamp the blade so that both cutting edges, 10, thereof will be in operative relation with respect to the teeth, 14, and intervening spaces, 15, of the guard-plate.

From the foregoing it will be seen that the operation of assembling the parts is simple and that no threaded fastenings are employed or necessary to secure the parts together, and also that the parts may readily be separated for cleaning. It will also be seen that the longitudinal grooves and ribs on the several parts serve to accurately adjust the cutting edges of the blade with respect to the guard and prevent lateral displacement of parts.

Having thus described my invention what I claim and desire to secure by Letters Patent is,—

1. In a razor the combination with a handle, of a blade-carrying bar pivotally connected to the handle and having a longitudinal groove which latter is provided with positioning devices; a blade having a groove at one side and a rib at the opposite side which latter enters the groove in the bar, the blade having position against the carrying bar between the free end of the latter and the positioning devices in the groove of the

carrying bar whereby to leave the said positioning devices exposed; a guard plate having a rib to enter the groove of the blade and said plate also having a reduced end to project beyond the inner end of the blade and the said reduced end of the guard plate having positioning devices to engage the positioning devices on the carrying bar and a clip plate to clamp the reduced end of the guard plate against the bar and hold the blade in place.

2. In a razor the combination with a handle, of a blade-carrying bar pivotally connected to the handle and having a longitudinal groove with positioning devices located in the groove and also having a hook turned back over at its free end which hook overlies but is spaced from the longitudinal groove; a blade having a groove at one side and a rib at the opposite side which latter enters the groove on the bar, one end of the blade projecting beneath the said back turned hook and the other end terminating at a point between the hook and the positioning devices in the groove of said carrying bar whereby to leave said devices uncovered; a guard plate having a rib to enter the groove of the blade and one end of the guard plate also projecting beneath the back-turned hook on the carrying bar while the other end of said guard plate has a reduced portion to be engaged by the positioning devices on the carrying bar and means to clamp the reduced portion of the guard plate and the bar together.

3. In a razor the combination with a handle, of a blade carrying bar pivotally connected to the handle near one end and having a longitudinal groove at one side and longitudinal side flanges along a portion only of its length; a blade having a longitudinal groove at one side and a longitudinal rib at the other side which rib seats in the groove of the carrying bar; a guard plate having a rib at one side to engage the groove of the blade and said guard plate being provided with a reduced end to seat against the blade carrying bar and a clip plate having its opposite sides engaging the side flanges on the carrying bar and clipping the reduced end of the guard plate against the bar whereby to hold the blade in place.

In testimony whereof I affix my signature in presence of two witnesses.

HUGH P. McMILLAN.
